(57) **CLAIM**

The ornamental design for a six-sided carton with a handle, as shown and described.

DESCRIPTION

FIG. 1 is a perspective view of the six-sided carton with a handle;

FIG. 2 is a front view of the six-sided carton with a handle; the rear view being identical to the front view;

FIG. 3 is a right side view of the six-sided carton with a handle; the left side view being identical to the right side view;

FIG. 4 is a top view of the six-sided carton with a handle; and, FIG. 5 is a bottom view of the six-sided carton with a handle. The broken lines represent the boundaries of the claim and form no part of the claimed design.
